UNITED STATES PATENT OFFICE.

JAMES S. ZERBE AND ANDREW J. WHITE, OF CINCINNATI, OHIO.

COTTON-SEED HULLER AND SEPARATOR.

SPECIFICATION forming part of Letters Patent No. 289,365, dated November 27, 1883.

Application filed September 24, 1883. (No model.)

To all whom it may concern:

Be it known that we, JAMES S. ZERBE and ANDREW J. WHITE, both of Cincinnati, in the county of Hamilton and State of Ohio, have 5 invented a new and useful Improvement in Cotton-Seed Hullers and Separators, which improvement is fully set forth in the following specification and accompanying drawings, in which—

10 Figure 1 is an end view of our cotton-seed huller. Fig. 2 is a front view of the same. Fig. 3 is an enlarged cross vertical section of the feeding and hulling box; Fig. 4, a perspective view of the hulling cylinder or roll; Fig. 5, a perspective view of the concave and ribs; and Fig. 6, a front view, partly in section, of the hulling-roll and shaft, showing the solid boxing in which it is journaled.

15 The object of the present invention is to provide a cheap and efficient machine for hulling cotton-seed and separating the same; and it comprises, among other parts, a solid roll provided with ribs operating within a casing, which has concaves, upon which are ribs, so that as the cotton-seed is fed into the rolls by 20 means of a feed-roll the ribs split the seed and permit the germ to be separated from the hulls. The seed, as it passes from the roll, falls into a conveyer, which rotates within a perforated 25 concave shell, thus separating the germ from the hulls, the latter passing into a suction-fan, from which it is expelled through tubes into the furnace, or to some convenient point away 30 from the machine.

35 In the accompanying drawings, A represents the main frame, which carries the hulling-roll and case B. The frame C supports the rear end of the perforated casing D, within which the screw-conveyer E operates. The frame A 40 supports the forward end of the perforated casing D.

The casing F B O J, which contains the hulling and feeding rolls, is of peculiar construction, and it is in this, among other respects, 45 that this machine is superior to others for the same purpose. The base F, which forms the end pieces for the hopper or case, has journaled therein the shaft G of the hulling-roll. Instead of providing adjustable boxing, as is 50 customary in machines of this class, we con-

struct a solid boxing, H, larger than the shaft, and after the shaft is placed in the boxing and properly adjusted, Babbitt metal I is run around the shaft. By this means no other adjusting is required, and the roll will be firmly 55 held in position. The shell J of the casing on the rear side conforms to the arc of the roll K within. On the forward side we place two concave pieces, L L, each of which is provided with two or more ribs, M, which will be further explained hereinafter in connection with the roll K. Above the hulling-roll K is the feed-roll N. It will be observed that the front face, O, at the upper part of the casing, is exactly vertical and on the same plane as the 60 shaft G of the hulling-roll. The feed-roll N is located within the casing, so that its periphery touches the side O, while the side P of the case is of the same arc as the roll, and extends over to a point, P', directly above the 65 shaft N' of the feed-roll, from which point the side Q extends upwardly and rearwardly, so as to form a hopper or receptacle for the seed. It will be observed that the feed-roll N turns to the left, or in the direction shown by the 70 dart. The roll N being corrugated, as shown at R, the seed will fall therein, and as the seed tends to fall to the right against the vertical side O of the casing, the turning of the roll has a tendency to constantly raise the seed and loosen 75 the same, so that when any point or rib of the roll reaches the corner P' the pressure of the mass of seed above will not cause the seed to crush between the roll and the casing and choke the machine or ball the seed. We find proper 80 feeding to be an important matter, especially where the seed has not been perfectly linted; but by the arrangement here shown the most perfect feeding is accomplished, and there is 85 no liability of choking.

90 Referring now to the hulling-roll K, it will be seen that in this instance six ribs, a, are shown, equidistant apart. These ribs have their edges b projecting out, preferably, about one-eighth of an inch, or slightly less, and a straight line 95 is drawn from the base of one rib to the base of the next, as shown at c. The concave pieces L on the forward side of the casing have on their inner surfaces two or more ribs, M. These ribs are about an eighth of an inch in height, 100

and the spaces L' between the ribs are concaved, so that the spaces formed by the straight faces c of the roll K and the concave plates L will furnish sufficient draft to take in the seed 5 as rapidly as it is fed to the hulling-roll.

We also call particular attention to the fact that the hulling-roll K and the ends of the casing F which receives the concave plates L , are of the same arc, and since the ribs M of 10 the concave plates are flush with its end surface, M' , the plates L , when placed on the case F and bolted thereto, require no other adjustment.

Below the hulling-roll is the conveyer-box 15 D , perforated as shown, within which is placed the screw-conveyer E . At the rear end of the machine is a suction-fan, S , which is designed to receive the hulls and convey them either to the furnace or remove them to some convenient point away from the machine. 20

To operate the mechanism we provide a counter-shaft, T , on the frame A , and by means of the belts U V and their pulleys transmit the speed necessary to rotate the feed-roll N ; also, 25 by means of the belt W , motion is transmitted to the screw-conveyer E .

It is obvious that the feed roll and conveyer, or either, may be operated by a counter-shaft from the main driving-belt, if it is desired.

30 What we claim is—

1. The herein-described hulling-roll, which consists of a solid roll, K , having slightly-projecting ribs a and intervening straight spaces c , substantially as herein set forth.

2. The herein-described concave, consisting 35 of plates L , having the ribs M , the flush-surfaced ends M' , and the concave intervening spaces L' , substantially as described.

3. The combination of the solid roll K , having ribs a and straight spaces c , with the concave plates L , substantially as described. 40

4. The combination of the hulling-roll K and the casing $F B O J$, the rear part, J , conforming to the arc of the roll, with the concaved pieces L , having ribs M and flush surfaced 45 ends M' , substantially as described.

5. The combination of the hulling-roll and concave with the fluted feed-roll N and seed hopper having a vertical front face, O , inclined upper rear face, $Q P'$, and the curved 50 outwardly and downwardly extending lower rear face, P , substantially as described.

In testimony that we claim the foregoing we have hereunto set our hands this 18th day of September, 1883, in the presence of witnesses. 55

JAMES S. ZERBE.
ANDREW J. WHITE.
